C. A. ROWLEY

DRAWING AND FLATTENING TABLE FOR SHEET GLASS

Filed Jan. 30, 1924

UNITED STATES PATENT OFFICE.

CLIFFORD A. ROWLEY, OF TOLEDO, OHIO, ASSIGNOR TO THE LIBBEY-OWENS SHEET GLASS COMPANY, OF TOLEDO, OHIO, A CORPORATION OF OHIO.

DRAWING AND FLATTENING TABLE FOR SHEET GLASS.

Application filed January 30, 1924. Serial No. 689,398.

To all whom it may concern:

Be it known that I, CLIFFORD A. ROWLEY, a citizen of the United States, residing at Toledo, in the county of Lucas and State of Ohio, have invented new and useful Improvements in Drawing and Flattening Tables for Sheet Glass, of which the following is a specification.

This invention relates to improvements 10 in the art of drawing sheet glass, and more particularly to an improved apparatus for drawing and flattening the glass sheet.

In the patent to Colburn, 1,248,809, granted December 4, 1917, is disclosed a process 15 and apparatus for drawing the sheet of glass upwardly from a pool of molten glass, bending the sheet while still plastic about a cooled bending roller, and then carrying the sheet horizontally over a traveling drawing and flattening table and thence into the leer. The present invention relates to a new 20 and improved form of the drawing and flattening apparatus and is especially adapted for use in a sheet drawing system such as 25 just described.

The improved drawing table comprises a plurality of closely positioned parallel rollers, preferably driven, the upper sheet carrying portions of the cylindrical surfaces of 30 the rollers all being tangent to the same horizontal plane. These rollers carry the main central body portion of the sheet. In combination with the rollers, each edge portion of the sheet is gripped between a pair of 35 endless linked belts which draw and support these edge portions of the sheet. Preferably, the two pairs of linked belts diverge from one another in the direction of travel of the sheet so that additional lateral tension is imparted to the sheet as it passes over 40 the lower flattening table. This lateral tension assists in flattening the sheet, and also counteracts the tendency of the still somewhat plastic sheet to sag at the unsupported 45 points between adjacent rollers.

The objects and advantages of the invention will be more clearly understood from the following detailed description of one approved form of the apparatus.

50 In the accompanying drawings:

Fig. 1 is a side elevation, partly in section, of portions of the drawing and flattening mechanism.

Fig. 2 is a plan view of the drawing and

flattening mechanism, and adjacent portions 55 of the sheet-drawing system, the upper chain loops being omitted.

Fig. 3 is a transverse section on an enlarged scale through one pair of edge-drawing chains and adjacent ends of one of the 60 rollers.

Glass sheet 1 is drawn upwardly from the pool of molten glass 2, and then bent over cooled bending roller 3 into the horizontal plane. After passing over certain intermediate supporting rolls such as 4, sheet 1 passes through the drawing and flattening mechanism forming the subject-matter of this invention, and then passes onto the conveying 65 rollers 5 in leer 6.

The main sheet-supporting portion of the drawing and flattening table consists of a plurality of closely positioned, parallel, cylindrical rollers 7. These rollers may be in the form of long continuous cylinders as 70 shown at 7, or may be in the form of a series of spaced, short, cylindrical discs 8, mounted or formed on a supporting shaft 9. The discs 8 on one shaft move in the spaces 75 between discs 8 on the adjacent shafts. In this way each adjacent pair of shafts 9 may be brought more closely together, and the length of the unsupported stretch of glass sheet between adjacent rollers is considerably diminished. As shown in the present drawings that portion of the table nearest the sheet source, where the glass is most plastic, is made of the interlocking discs just described, whereas the opposite end of the table where the sheet has become cooler and 80 more self-supporting, is made of a series of the cylindrical rollers 7. Obviously, the entire table could be made of the interlocking discs, or the entire table could be made 85 of cylindrical rollers 7, and it is to be understood that the present invention covers the use of any of these combinations of rollers. The supporting shafts 9 for the several rollers project through the side walls 11 and 12 of the machine and are rotatably mounted in the continuous bearing blocks 13 and 14 mounted at the outer sides of the machine.

These supporting rollers may be idlers, in which case they should be mounted on roller-bearings. However, the rollers are preferably driven, to assist in drawing the sheet. One end of each shaft 9 is provided with a worm wheel driven from a worm 15

mounted on a driving shaft 16 or 17. The sheets to sag between adjacent supporting similar shafts 16 or 17 at the two sides of the machine are geared together, for example by the sprockets 18 and connecting 5 chain 19, so as to turn simultaneously and at the same speed. As here shown, alternate rollers are driven from alternate sides of the machine. This arrangement is merely to provide room for the driving gearing 10 for the closely positioned rollers. Obviously, gearing could be arranged to drive all of the rollers from the same side of the apparatus.

Each edge portion of the glass sheet 1 is 15 supported upon a continuous belt conveyor, here shown as a linked chain 20. This chain is in the form of an endless loop traveling over suitable sprockets 21 and 22, and the upper sheet-carrying run of the 20 chain being slidably supported upon the upper horizontal surface of a frame-bar 23. The shafts 9 for the several rollers project through openings 24 in this bar or track-way 23. Preferably, the supporting 25 sprockets 21 and 22 and the supporting trackway 23 for each of the conveyors 20 are positioned in a vertical plane which diverges somewhat in the direction of travel of the sheets, from the center-line of glass sheet 30 1. In other words, the conveyor chains at the two sides of the sheet separate slightly from one another as they move forward with the sheet. The outermost links of chain 20 are provided with downwardly extending flanges 25 which engage the outer edges of tracks 23 to compel the chains to move along their diverging courses against the resisting action of the glass sheet 1 carried thereby.

40 A second pair of loop chains 26, which may be of any suitable form having the necessary weight, are carried by sprockets 27 and 28, and the lower loosely hanging run of each chain loop rests its weight upon the edge portion of the sheet 1 above the supporting chain 20. In this way the edge portion of the sheet is gripped between the two chains 20 and 26 which support and hold it flat in the horizontal plane. The 45 two chains 20 and 26 are driven at the same linear speed, which speed is the same as the peripheral speed of the several supporting rolls 7 or 8. The outer links of the upper chain loops 26 have flanges 29 traveling behind fixed cam rails 30. These co-operating flanges and cam rails compel 55 chains 26 to follow the same diverging paths as supporting chains 20.

The pairs of chain loops 20 and 26 not 60 only support and draw along the edge portions of the sheet, but also tend to draw these edges laterally and apply a sidewise stretching tension in the body of the sheet. This tension assists in flattening the sheet 65 and counteracts the tendency of the moving

rollers. When the sheet 1 has become set, and has lost its plasticity to an extent that it is incapable of being stretched laterally, the edges of the sheet will slip or draw inward between the two chains 20 and 26, but there will be a continual lateral pull on the sheet which tends to hold it flat and prevents sagging.

The main central portion of the sheet is 75 supported during its setting and flattening period upon the rotating rollers 7 or 8. Thus the points of support of the sheet are continually changing, and the somewhat 80 plastic sheet does not have time to settle into holes or depressions in the supporting member and become marred thereby, as is sometimes the case where the entire sheet is supported during the flattening period upon a meshed or linked chain which moves 85 with the sheet.

I claim:

1. In a sheet glass drawing apparatus, a supporting and flattening table for the moving sheet, formed of a plurality of closely 90 positioned parallel rollers, the upper sheet-supporting surfaces of the rollers all lying in the same plane, in combination with continuous means at the sides of the table for supporting and drawing longitudinally the 95 edge portions of the sheet.

2. In a sheet glass drawing apparatus, a supporting and flattening table for the moving sheet, formed of a plurality of closely 100 positioned parallel positively driven rollers, the upper sheet-supporting surfaces of the rollers all lying in the same plane, in combination with continuous means at the sides of the table for supporting and drawing 105 longitudinally the edge portions of the sheet.

3. In a sheet glass drawing apparatus, a supporting and flattening table for the moving sheet, formed of a plurality of closely 110 positioned parallel rollers, the upper sheet-supporting surfaces of the rollers all lying in the same plane, in combination with a pair of link belts at each side of the table for supporting and drawing the edge portions of the sheet.

4. In a sheet glass drawing apparatus, a supporting and flattening table for the moving sheet, formed of a plurality of closely 115 positioned parallel positively driven rollers, the upper sheet-supporting surfaces of the rollers all lying in the same plane, in combination with a pair of link belts at each side of the table for supporting and drawing the edge portions of the sheet.

5. In a sheet glass drawing apparatus, means for gripping the edge portions of the sheet, means for moving the gripping means longitudinally with the sheet to draw the sheet from its source, means for simultaneously moving the gripping means laterally 125 130

to tension the sheet laterally, and a plurality of rollers intermediate the two sets of edge-gripping devices for supporting the main central portion of the sheet.

5 6. In a sheet glass drawing apparatus, means for gripping the edge portions of the sheet, means for moving the gripping means longitudinally with the sheet to draw the sheet from its source, means for simultaneously moving the gripping means laterally to tension the sheet laterally, and a plurality of positively driven rollers intermediate the two sets of edge-gripping devices for supporting the main central portion of the sheet.

10 7. In a sheet glass drawing apparatus, endless draw-members for gripping the opposite faces of the edge portions of the sheet, to support and draw the sheet lengthwise, means for causing the opposite sets of draw-members to move away from one another to tension the sheet laterally, and a plurality of rollers intermediate the two sets of draw-members to support the main central portion of the sheet.

15 8. In a sheet glass drawing apparatus, endless draw-members for gripping the opposite faces of the edge portions of the sheet, to support and draw the sheet lengthwise, means for causing the opposite sets of draw-members to move away from one

another to tension the sheet laterally, and a plurality of positively driven rollers intermediate the two sets of draw-members to support the main central portion of the sheet.

20 9. In a sheet glass drawing apparatus, four endless chains of gripping devices, each edge of the glass sheet being gripped between, and supported and drawn lengthwise by two of the chains, means to cause the opposite pairs of chains to move away from one another to tension the sheet laterally, and a plurality of rollers intermediate the two sets of draw-members to support the main central portion of the sheet.

25 10. In a sheet glass drawing apparatus, four endless chains of gripping devices, each edge of the glass sheet being gripped between, and supported and drawn lengthwise by two of the chains, means to cause the opposite pairs of chains to move away from one another to tension the sheet laterally, and a plurality of positively driven rollers intermediate the two sets of draw-members to support the main central portion of the sheet.

Signed at Toledo, in the county of Lucas and State of Ohio, this 26th day of January, 1924.

CLIFFORD A. ROWLEY.
